UNITED STATES PATENT OFFICE.

GEORGE HENRY WHEARY, OF RACINE, WISCONSIN.

WARDROBE-TRUNK.

1,157,652.

Specification of Letters Patent.

Patented Oct. 19, 1915.

Application filed January 2, 1914. Serial No. 809,809.

To all whom it may concern:

Be it known that I, GEORGE H. WHEARY, a citizen of the United States, and resident of Racine, in the county of Racine and State of Wisconsin, have invented new and useful Improvements in Wardrobe-Trunks, of which the following is a description, reference being had to the accompanying drawings, which are a part of this specification.

- 10 This invention relates to improvements in wardrobe trunks in which the trunk is divided vertically, medially into two sections which are hinged together and are adapted to be swung laterally to open position to gain access to the interior of the sections. In trunks of this type one of the sections is usually divided into drawers and other compartments and the other section is usually adapted to hold the wardrobe and is usually 15 provided with rails and garment hangers suspended thereon which may be withdrawn from the section while suspended on the rails. It is very desirable in trunks of this type to provide a top cover for the wardrobe section which may be swung to open 20 position to permit the convenient removal of the garments therefrom, and in the past, trunks have been constructed in one form in which an upwardly opening cover was 25 hinged to the rear vertical wall of the wardrobe section, and in another form in which the whole end of the trunk was hinged to one of the sections and was adapted to be 30 swung upwardly to open position. Both of these forms were found to be not as strong 35 as desired and required the sections to be spaced from the wall to permit the covers to be swung upwardly. The last mentioned form was also found undesirable due to the 40 size and weight of the cover and the possibility of the cover accidentally falling and injuring the user.

It is one of the objects of the present invention to overcome the before mentioned 45 objectionable features and provide a wardrobe trunk of the type mentioned which is of simple construction, is strong and durable and is well adapted for the purpose desired.

A further object of the invention is to 50 provide a wardrobe trunk in which the upper end cover of the wardrobe section is hinged to the non-movable end of the other section and is so constructed and arranged as to reinforce and brace the wardrobe section of the 55 trunk.

A further object of the invention is to

provide a wardrobe trunk in which the upper cover to the wardrobe section may be swung to open position, and, which, when in open position will not project laterally so 60 beyond the vertical walls of the trunk so that it is not necessary to move the trunk away from a wall to open same.

A further object of the invention is to provide a wardrobe trunk having means for 65 holding garments suspended on hangers mounted therein in position to prevent their disarrangement during transportation.

A further object of the invention is to provide a wardrobe trunk in which it is only 70 necessary to unlock one cover to gain access to a means controlling the locking of the two sections together.

With the above and other objects in view, the invention consists of the improved wardrobe trunk and its parts and combinations as set forth in the claims and all equivalents 75 thereof.

In the accompanying drawing in which the same reference characters indicate the 80 same parts in all of the views:

Figure 1 is a front view of the improved trunk, a part broken away to show interior construction; Fig. 2 is a rear view thereof, the wardrobe section of the trunk being 85 shown in section and its upper cover being indicated in open position by dotted lines; Fig. 3 is a top view of the trunk in partly open position, the upper cover being shown in open position and partly broken away; 90 and Fig. 4 is a rear view of a modified form of the upper portion of the trunk, the wardrobe section being shown in section and the upper cover being indicated in partly open 95 position by dotted lines.

Referring to the drawing the numeral 8 indicates the trunk body generally which is divided centrally, vertically to form a body section 9 and a wardrobe section 10 hinged thereto and arranged to be swung horizontally to open position. The upper end 11 of the body section 9 is fixed or immovably connected to the body section 9 and at its front edge 12 has a wardrobe section upper cover 13 hinged thereto which is adapted to close the upper open end 14 of the wardrobe section. The upper or top cover 13 is provided with deeply flanged front and side edge portions 15 which overlap the upper end portion of the wardrobe section 10 when said section is in closed position, and the end portion of said section is recessed 110

or offset as indicated by the numeral 16 to receive said cover. The body section 9 is provided with a metal flange 17 extending all around the front edges of the body which 5 overlaps the wardrobe section when in closed position and also the inner hinged and flanged edges of the upper cover when said cover is swung to closed position. This construction reinforces and securely binds the 10 wardrobe section to the firm end of the body section and forms a strong structure well adapted to withstand the hard usage which trunks are ordinarily subjected to during transportation. The lower edge portion of 15 the upper cover is also provided with a metal flange 18 which overlaps the unrecessed portion of the upper end of the wardrobe section and further reinforces the structure.

20 The two trunk sections are locked together at their lower end portions by a spring bolt lock 19 which is controlled by a slidable rod 19 mounted within the wardrobe section and having an operating finger 20 which 25 projects through the recessed portion of the said section. This finger is covered by the flange 15 of the upper cover when the said cover is in closed position so that it cannot be actuated until the cover lock 21 has been 30 unlocked and the said cover swung to open position. The trunk is also provided with other locking and corner fixtures not necessary to be specifically described.

Hanger tracks 22 mounted in the upper portion of the wardrobe section are provided with hinged extensible ends 23 which may be swung upwardly and locked in horizontal position in a manner now well known in the art to permit garment hangers 24 slidably mounted on said tracks to be slid out of the trunk section and upon the extensible ends. These hangers are adapted to have garments suspended thereon and when in position within the trunk they are kept from 40 becoming disarranged by means of a pad 25 interposed between the cover and the hangers and into which the hangers embed when the cover is closed. This pad may be carried by the cover as shown in the drawing or it may be independent of the cover, if desired.

In the modified form of trunk shown in Fig. 4 the deep cover flange and the recessed wardrobe section are omitted and in lieu thereof the edge of the cover is provided with a metal flange 26 which overlaps the upper portion of the wardrobe section when the parts are in closed position.

From the foregoing description it will be seen that the wardrobe trunk is well adapted for the purpose described.

What I claim as my invention is:

1. A wardrobe trunk, comprising a trunk body divided vertically medially into two sections which are hinged together, one of

said sections having an open end and the other section having a closed end, and a cover hinged to the closed end section and adapted to extend only over the open end section when the two sections are in closed 70 position.

2. A wardrobe trunk, comprising a trunk body divided vertically into two sections which are hinged together, one of said sections having an upper open end and the 75 other section having an upper closed end, and a cover hinged to the forward edge portion of the closed end section and adapted to extend over and close the open end of the other section when the two sections are in so closed position.

3. A wardrobe trunk, comprising a trunk body divided vertically into two sections which are hinged together, one of said sections having an upper open end and the 85 other section having an upper closed end, the open end section having its upper edge portion recessed, and a cover hinged to the upper forward edge portion of the closed end section and adapted to extend over the 90 open end section when the said sections are in closed position, the said cover being provided with a depending flange which overlaps the open end section and extends into the recess of said section.

4. A wardrobe trunk, comprising a trunk body divided vertically into two sections which are hinged together, one of said sections having an upper open end and the other section having an upper closed end, 100 the closed end section provided with a projecting flange which extends all around the front edges of said section and which is adapted to overlap the forward edges of the other section when both sections are in closed 105 position, the open ended section having its upper portion recessed, and a cover hinged to the upper forward edge portion of the closed end section and adapted to swing over the open end section when the said sections 110 are in closed positions, the said cover being provided with a depending flange which overlaps the open end section and extends into the recess of said section, the rear edges of the cover adapted to be overlapped by the 115 projecting flange of the closed end section.

5. A wardrobe trunk, comprising a trunk divided vertically into two sections which are hinged together, one of said sections having an upper open end and the other section having an upper closed end, a cover hinged to the upper forward edge of the closed end section and adapted to swing over and close the open end section when the sections are in closed position, garment 120 hangers mounted in the open ended section near the cover; and a pad interposed between the cover and the hangers and into which the hangers embed.

6. A wardrobe trunk, comprising a trunk 125

body divided vertically into two sections which are hinged together, one of said sections having an open end and the other section having a closed end, a cover hinged to the closed end section and adapted to swing over and close the open ended section when the sections are in closed position, a lock for securing the cover in closed position, and a locking means for locking the two sections in closed position and having a controlling member exposed to view when the cover is in open position.

7. A wardrobe trunk comprising two vertical hinged together sections, one having

an open top and the other a permanently closed top with a cover hinged to its free edge adapted to be closed down upon the open top of the first-mentioned section when the two sections are closed together, and means for securing said cover in closed position.

10

In testimony whereof, I affix my signature, in presence of two witnesses.

GEORGE HENRY WHEARY.
